METHOD OF MAKING PACKING RINGS

Albert W. Wenzel, West Orange, N. J.

Application April 11, 1936. Serial No. 73,837

9 Claims. (Cl. 29—156.6)

This invention relates to the method of manufacturing packing rings, and is a continuation in part of previously filed application S. N. 710,755 of February 10, 1934.

The objects of the invention are to provide an improved method for making rings of lasting quality; to provide a method which will produce a ring subject to minimum distortion under severe heat conditions such as encountered in internal combustion engines; to provide a method wherein the tension in the ring is made permanent; to provide a method which affects the molecular structure to stabilize the same beyond a point at which engine heat will cause no further disturbance; to provide a method which takes into consideration the internal inequalities of tension of the molecular structure; to obtain a closure of the ring and at the same time permit the ring to assume a natural shape which it assumes with free exercise of its internal stresses, preparatory to machining; to hold the ring in its natural shape which it assumed when closed while machining the same; to retain the inherent resiliency of the ring by utilization of pressure sufficient to disturb a part of the metal; to apply this disturbance throughout the length of one surface of the ring; to avoid applying a pressure which will create burrs; to apply a pressure without fracturing the metal; to obtain a burnishing compression; to obtain a flow of the metal under action of the burnishing and a molecular rearrangement; to create the molecular disturbance of successive molecules in a circumferential juxtaposition; to reduce the heretofore necessary number of operations for making a ring; to secure simplicity of construction, operation and fulfillment of the several steps requisite to the method; and to obtain other advantages and results as may be brought out in the following description.

In the accompanying drawing in which like numerals of reference indicate similar parts throughout the several views:

Figure 1 is an elevation of a ring which has been cut to provide the usual expansion gap, but otherwise in its crude condition;

Figure 2 shows the ring of Fig. 1 drawn together to close the said gap;

Figure 3 illustrates the next step of the method wherein one or more rings are held frictionally by their flat surfaces ready to machine the outside cylindrical surface of the same;

Figure 4 illustrates the next step wherein the rings are similarly clamped to be internally machined;

Figure 5 shows a ring which has been machined

both on its outside and inside circumferences and which is being compressed in accordance with the present invention;

Figure 6 is a sectional view on line 6—6 of Fig. 5;

Figures 7 and 8 are views similar to Figs. 5 and 6 showing a different compression tool;

Figure 9 is a similar sectional view of the ring after completion of the compression step;

Figure 10 is a similar sectional view of the ring 10 of Fig. 9 in a chuck as held for grinding the side faces of the ring; and

Figure 11 is a view similar to Fig. 8, showing a modified construction of ring and tool.

Heretofore in the manufacture of packing 15 rings, a method has been employed for tensioning the rings known as hammering. The method has applied a compressive stress at separated points along the inner circumference of the usual normally expanded piston ring, but between the 20 points of compression the metal of the ring has remained in its original state. By virtue of the hammered parts of the ring alternating with un-hammered parts, the molecular structure of the metal is irregularly disturbed, and while this has 25 obtained a certain beneficial result in tensioning the ring, it has had a detrimental effect in that the rings warp readily under engine heat. According to the present invention, the ring is 30 constructed to be a perfect circle when closed and to have perfect tension throughout the length of its treated surface. The usual piston ring is treated on its inner circumference so as to stand normal expanded, but other packing rings, such as are to stand normally contracted, are 35 treated upon the outer circumference. It is likewise possible to treat the ring on its side or flat faces, or upon one or more edge corner, or upon a bevel or round. Therefore, while the selected 40 illustration herein shows treatment on the inner circumference, it is to be understood the invention is not restricted thereby.

In proceeding with the manufacture of rings according to my invention, the blank may be an iron casting in the shape of an annulus. In 45 Figure 1, I have illustrated such an annulus, designated by the numeral 10 upon which the first operation has been performed, namely cutting the same through at 11 so that the annulus may be resiliently compressed. While I have shown the 50 cut as made diagonally with respect to the radius, any suitable cut may be made for obtaining the desired joint or overlap for the ends thus made. After completion of this first step, the ring is 55 next drawn together under natural conditions,

as shown in Figure 2 by any suitable tool 12, here shown as including a band 13 which will extend around the annulus and the ends of which can have tension applied thereto in opposite directions. The tool will accordingly apply a closing tension to the ring in a circumferential direction enabling the ring to assume its natural shape henceforth to be assumed when the ring is closed. In other words, if the internal stresses and strains 10 tend to make the casting oval or lopsided, the ring assumes that shape while gripped by the tool before and while being introduced into the clamp of Figure 3 (described below) and retains that shape even after said clamp is applied. 15 Then, when the outer surface of the ring is machined off, the ring becomes a perfect circle and thereafter will always naturally assume its shape as a perfect circle when closed in an engine cylinder.

20 As indicated in general terms above, while the ring is drawn together to its naturally assumed shape when closed, it is clamped by its side or flat faces with adequate force to retain the ring in exactly the shape it assumed under influence 25 of the tool. The tool may then be removed and the clamping utilized to retain the ring both closed and in its assumed shape for the following machining operations. The clamping of the ring is illustrated in Figure 3, wherein numeral 14 indicates a base or clamping plate in the nature of a face plate with a flat face against which one side of the ring 10 may be engaged. A spider-like mandrel 15 positioned upon a central bolt 16 protruding from the face plate may be utilized 30 for approximately centering the ring with respect to clamping or face plate 14. In practice, I prefer to make the mandrel 15 and bolt 16 of sufficient length so that a plurality of rings may be applied at one time, said rings resting against 35 each other side by side and being clamped by an outer clamping plate 17 applied upon the bolt next the outermost ring and caused to squeeze the rings together by applying a nut 18 to the bolt. The outer clamping plate 17 is of a diameter greater than the inner diameter of the ring, but of less diameter than the outer diameter of 40 the ring. A margin of the ring next the outer circumference therefore may be seen projecting beyond the circumference of the outer clamping plate.

It will be understood that the outer curved surface of the several rings thus held by the clamp provides a substantially cylindrical surface. The clamp with the rings may then be put in a lathe 55 or other suitable machine and the outer surface of the rings turned down to a depth below the chilled or spongy layer of the casting to a surface where the metal is healthy, for instance to surface 19 where the crusty surface of the casting 60 and the imperfections which exist in that part thereof have been eliminated. All of the rings are thus brought to a perfect cylindrical formation of desired size and healthy surface.

While outer clamping plate 17 still retains the 65 machined rings secured in perfect cylindrical condition, a clamping collar 20 which has a middle opening 21 large enough to receive clamping plate 17 therein, is applied to the margin of the piston ring projecting beyond the edge of 70 clamping plate 17, and is then secured by bolts 22 and nuts 27 with respect to the base clamping plate 14. After this clamping collar 20 is secured firmly, the outer clamping plate 17 and mandrel 15 as well as bolt 16 may be removed. This enables the inner surface of the several piston rings

to be machined, if desired, for instance to a healthy surface 23, thereby taking off the crust of the castings at the inside of said rings and removing the imperfections of the chilled and spongy layer to a desired depth. When this operation is completed, the clamping collar 20 may be removed, if desired, and all further operations performed individually upon the rings. 5

As illustrated in Figures 5 and 6, the next operation upon the ring is to obtain a molecular 10 disturbance substantially throughout the length of one surface of the ring. This operation may be performed upon such surface or surfaces of the ring as found desirable or necessary for the tension desired. The step in its preferred performance contemplates obtaining in the finished ring at least one surface which is compressed for the entire circular length of that surface. As one means of accomplishing this result upon a selected surface, for instance the inner circumference of the ring, a tool 24 shown in the shape 20 of a roller, may be utilized. While this roller is also illustrative of a progressive application of the tension, it is not restricted thereto, as the tension may be otherwise applied, for instance by 25 an expanding tool and progressive from several points or with a simultaneous pressure throughout the length of the surface.

Describing the illustrated embodiment, the tool 24 is shown as having a central bead 25 of less 30 width than the ring. This tool is applied to the inner circumference of the ring and caused to travel entirely around that circumference with suitable pressure so as to create a continuous depression or groove 26 in the ring. Bead 25, being 35 of less width than the ring, avoids turning up a bur at the side face of the ring. However the molecular disturbance and compression is continuous throughout the length of the inner circumference and thus obtains a perfect tensioning without any likely distortion or warping in use. The molecular disturbance involves successive juxtaposed molecules in a direction circumferentially of the ring, and, for want of a better term, may be referred to as burnishing. It 40 is within the scope of my invention to apply the burnishing action not only as above described, but at successive intervals spaced by unburnished intervals, as well as by a continuous burnishing terminating at a distance from one or both ends 45 of the ring. A burnishing partly upon one surface and partly on another, a burnishing partly upon one corner edge and partly on another, as well as a combination of burnishing partly on a 50 face and partly on a corner or upon several faces and one or more corners and conversely upon a plurality of corners and one or more faces may 55 be utilized.

While in the above description I have referred 60 to a tool under the specific designation of "roller" 60 it is to be understood that tool does not have to have, and preferably does not have a rotative movement while being applied to the ring. I deem it within the scope of the invention to permit the roller to rotate freely, however, to have 65 a partial rotation, should such be desired, but preferably not to rotate at all during the engagement in use with the ring. Its circular or roller shape has the benefit of enabling it to be readily applied in the machine and its angular 70 disposition changed by the operator as the roller surface wears at any one spot. More than mere rolling the tool on the surface is required; there must be a "flow" of the metal, that is, a slight 75 mound of metal forms in advance of the tool and 75

is pushed forward, like a wave, thereby obtaining a positive molecular displacement in the metal in a circumferential direction. This effect is best accomplished with no rotation of the tool being permitted. The tool has to be a blunt one so as not to cut the "mound" or "wave", and yet it may be less rounded than a roller. For instance, a fixed tool 24^a is shown in Figures 7 and 8 with a downwardly directed rounded or beaded end 25^a which will obtain the desired impression, flowing or burnishing of the metal of the ring.

It is within the scope of the invention to apply this pressure uniformly throughout the circular length of the ring or to vary the pressure in such manner as to obtain greater compression diametrically opposite the split or joint, and progressively lessening in both directions from this maximum pressure to a minimum pressure adjacent the split. Figure 9 illustrates the ring as having had the pressure applied continuously along the inner circumference, thereby forming burnishing, groove or depression 26 within the inner machined surface 25 as above described. The method performed as described above accomplishes the ultimate result with less operations than utilized in known previously used methods.

It is furthermore deemed within the scope of the present invention to utilize a tool 31 having a substantially straight surface transverse to the ring surface being treated and apply the same to a circumferential surface of the ring 29 which in cross-section is convex as at 30 (Fig. 11). This structure is the reverse of that shown in Figures 6 and 8 since there the convexity is upon the tool whereas the circumference acted upon is originally substantially cylindrical. In any instance, I also deem it within the scope of the invention and within the meaning of the description when referring to a continuous pressure, to employ a burnishing tool or roller or other means such as hammering for obtaining a compression of the metal of the ring at very close intervals, in other words, the roller if used does not have to be smooth, but may have its surface corrugated either in a circumferential direction or in an axial direction, or diagonally, or with crossing corrugations comprising a combination of any of those just mentioned, so close as to produce a substantially continuous effect, and especially where a sliding compression is effected between tool and ring while the tool is in compressive contact with the ring.

It is preferable, after the rolling, burnishing or compressing step above described, has been completed, to grind or otherwise finish the flat or side faces of the ring, not only to remove any bur which the compression step may have raised, but also to obtain a ring which has its side faces in planes and with the planes of the two side faces parallel to each other. It often occurs, upon compressing a ring to the shape which it assumes within a cylinder in use, that certain internal stresses cause the ring to warp or dish and thus have its side face or faces not truly within a plane, especially in rings of uneven cross-section. The warping may affect only the ends of the ring or may affect the entire ring. It is therefore a feature of the present invention to perform, as a final step, a grinding or other smoothing and truing operation upon the side faces of the ring under conditions of the ring as will exist when in use. For this purpose, the ring is squeezed with its ends substantially together into a chuck or other holding means 28

which preferably engages the ring entirely around its circumference but from which the ring projects at one side as clearly shown in Fig. 8. The projecting side of the ring is ground or otherwise treated and thereafter the ring is reversed so that the other side thereof can be similarly ground or treated. According to this invention, therefore, the ring is very accurate in all of its faces which engage either the piston or cylinder in use.

Obviously detail changes and modifications may be made in carrying out my improved method of manufacturing packing rings and in the apparatus employed in the accomplishment of that method without departing from the spirit or scope of the invention, and I do not wish to be understood as limiting myself thereto except as set forth in the following claims when construed in the light of the prior art.

Having thus described my invention, I claim:—

1. A method of manufacturing packing rings comprising first closing the ring by a circumferential tension, clamping the ring flatwise upon a member while thus closed, and machining said ring on both its outer and inner circumferences before releasing from said member.

2. A method of manufacturing packing rings comprising first closing the ring by a circumferential tension, clamping the ring flatwise upon a member with the outer circumference of the ring exposed, machining said outer circumference, and thereafter machining the inner circumference before releasing from said member.

3. A method of manufacturing packing rings comprising first closing the ring by a circumferential tension, clamping the ring flatwise with the outer circumferences of the ring exposed, machining said outer circumference, applying a clamp to the flat face of the ring outside of and without releasing the first clamp, removing the first clamp, and machining the inner circumference of the ring.

4. A method of manufacturing packing rings comprising applying a continuous sliding pressure throughout the length of one surface thereof with a differential of intensity transversely of said surface for obtaining a continuous molecular disturbance of the material throughout said length.

5. A method of manufacturing packing rings comprising applying a continuous sliding pressure to the inner circumference thereof for obtaining a continuous molecular disturbance of the material throughout the length of said inner circumference, said pressure being applied with maximum intensity parallel to and spaced from one longitudinal edge of said surface.

6. A method of manufacturing packing rings, comprising applying a burnishing sliding pressure upon the inner circumference of the ring in a circumferential direction for obtaining a molecular disturbance in the material of the said ring.

7. A method of manufacturing packing rings comprising burnishing a groove with pressure throughout the length of one surface of the ring for obtaining a molecular disturbance of the material throughout said length.

8. A method of manufacturing packing rings comprising first closing the ring by a circumferential tension, clamping the ring flatwise upon a member while thus closed, machining the ring on both its outer and inner circumference before releasing from said member, and thereafter applying a continuous pressure throughout the length of one surface of the ring for obtaining a

continuous molecular disturbance throughout said length.

9. A method of manufacturing packing rings comprising first closing the ring, clamping the 5 ring flatwise with the outer circumference of the ring exposed, machining said outer circumference, applying a clamp to the flat face of the ring out-

side of and without releasing the first clamp, removing the first clamp, machining the inner circumference of the ring, and applying a continuous pressure throughout the length of one surface of the ring for obtaining a molecular disturbance of the material throughout said length.

ALBERT W. WENZEL.
